UNITED STATES PATENT OFFICE

149,511

DESIGN FOR A COMBINED FRANKFURTER
SANDWICH AND STICK HANDLE

George E. Mitzel, Seattle, Wash., assignor to
M. & M. Food Products Company, Seattle,
Wash.

Application March 8, 1946, Serial No. 127,266

Term of patent 7 years

(Cl. D8—1)

To all whom it may concern:

Be it known that I, George E. Mitzel, a citizen of the United States, residing at Seattle, in the county of King, State of Washington, have invented a new, original, and ornamental Design for a Combined Frankfurter Sandwich and Stick Handle of which the following is a specification, reference being had to the accompanying drawing, forming part thereof.

Fig. 1 is a side view of a combined frankfurter sandwich and stick handle, showing my new design.

Fig. 2 is a top end view of the same.

Fig. 3 is a lower end view of the product,

I claim:

The ornamental design for a combined frankfurter sandwich and stick handle, as shown.
GEORGE E. MITZEL.
